UNITED STATES PATENT OFFICE.

THURE DAHL, OF NEW YORK, N. Y., ASSIGNOR TO LIGHTOLIER COMPANY, A CORPORATION OF NEW YORK.

DESIGN FOR A SHADE FOR LIGHTING-FIXTURES.

58,719.

Specification for Design.

Patented Aug. 30, 1921.

Application filed December 30, 1920. Serial No. 434,152. Term of patent 7 years.

To all whom it may concern:

Be it known that I, THURE DAHL, a subject of the King of Sweden, residing at New York city, in the county of New York and State of New York, have invented a new, original, and ornamental Design for Shades for Lighting-Fixtures, of which the following is a specification, reference being had to the accompanying drawing, forming part thereof.

Figure 1 is a side view of the shade applied to the fixture; and,

Fig. 2 is a perspective view of the shade.

I claim:

The ornamental design for a shade for lighting fixtures as shown.

THURE DAHL.
